CLAIM

The ornamental design for a spacer applied to reticle container as shown.

DESCRIPTION

FIG. 1 is a top-right-front perspective view of an embodiment of a spacer applied to reticle container.

FIG. 2 is an enlarged view of the structure identified by Circle 2 in FIG. 1.

FIG. 3 is an enlarged view of the structure identified by Circle 3 in FIG. 1.

FIG. 4 is an enlarged view of the structure identified by Circle 4 in FIG. 1.

FIG. 5 is an enlarged view of the structure identified by Circle 5 in FIG. 1.

FIG. 6 is an enlarged view of the structure identified by Circle 6 in FIG. 1.

FIG. 7 is a bottom-right-front perspective view of the spacer applied to reticle container depicted in FIG. 1;

FIG. 8 is a top view of the spacer applied to reticle container depicted in FIG. 1;

FIG. 9 is a bottom view of the spacer applied to reticle container depicted in FIG. 1;

FIG. 10 is a front view of the spacer applied to reticle container depicted in FIG. 1;

FIG. 11 is a rear view of the spacer applied to reticle container depicted in FIG. 1;

FIG. 12 is a left side view of the spacer applied to reticle container depicted in FIG. 1;

FIG. 13 is a right side view of the spacer applied to reticle container depicted in FIG. 1; and,

FIG. 14 is an exploded view of a reticle container including the spacer applied to reticle container depicted in FIG. 1. The broken lines showing in the figures are for illustrative purposes only and form no part of the claimed design.

1 Claim, 14 Drawing Sheets
